(57) **CLAIM**

The ornamental design for a “cosmetic applicator,” as shown and described.

DESCRIPTION

FIG. 1 illustrates an isometric view of a cosmetic applicator according to one embodiment of the invention;

FIG. 2 is a front view of the cosmetic applicator of FIG. 1;

FIG. 3 is an enlarged cross-sectional view taken along line 3-3 in FIG. 2;

FIG. 4 is a rear view of the cosmetic applicator of FIG. 1;

FIG. 5 is a left view of the cosmetic applicator of FIG. 1;

FIG. 6 is a right view of the cosmetic applicator of FIG. 1;

FIG. 7 is a top view of the cosmetic applicator of FIG. 1; and,

FIG. 8 is a bottom view of the cosmetic applicator of FIG. 1. The broken line showing of a shank illustrates a portion of the cosmetic applicator that forms no part of the claimed design.
